COLIN T. FINLAYSON, OF ALBANY, OREGON, ASSIGNOR TO HIMSELF AND ALFRED C. LOUD, OF SAN FRANCISCO, CALIFORNIA.

Letters Patent No. 95,385, dated September 28, 1869.

IMPROVEMENT IN PROPELLER-WHEELS.

The Schedule referred to in these Letters Patent and making part of the same.

To all whom it may concern:

Be it known that I, COLIN T. FINLAYSON, of Albany, in the county of Lynn, and State of Oregon, have invented a new and useful Improvement in Propeller-Wheels; and I do hereby declare that the following is a full, clear, and exact description of the construction and operation of the same, reference being had to the accompanying drawings, making a part of this specification, in which—

Figure 1 is a perspective view.

Figure 2 is an end elevation.

Figure 3, a longitudinal vertical section.

Figure 4, a view, in perspective, of the ship's bottom and wheel-guard.

Figure 5, a transverse vertical section.

Figure 6, other perspective views of the ship's bottom and guards.

Figure 7, a perspective view of the wheel.

This invention consists in placing in a ship's bottom, or beneath the line of light weight, within a case or chamber, fitting as closely as possible short of actual contact, a propeller-wheel of the construction herein-after described, the lower portion of the case projecting downward into the water when the wheel runs vertically, and having, in its lower edge, and not elsewhere, one or more perforations at the sides, and an opening in the rim, to the end that the wheel may, by its first few revolutions, expel the air from the enclosing-case, and form a vacuum therein; and that the water may thereupon rush in, through the perforations at each side, in powerful transverse currents, which strike the front concave faces of the buckets, by their first impact accelerating the velocity of the wheel, and, meeting at the middle of the rim of the wheel, form liquid bars, as it were, which are cut across by the sharp rear edges of the buckets, and sections thereof thrown out of the aforesaid opening in the lower part of the rim of the enclosing-case, by the concave rear faces of the buckets against the dense water outside, the reaction of which tends to still further increase the speed of the wheel.

The invention also consists in buckets projecting radially from the rim of the wheel, and having concave front faces, for the side current to strike against, as before described, and sharp cutting-edges coincident with the sides of the wheel, and concave rear faces, to throw the water bars to the rear.

In the drawings—

A is the ship, and

B, vertical cases, of any suitable material, placed longitudinally of the ship, and at any point in her length where it shall seem best—perhaps oftenest a little abaft midships, where paddle-wheels are usually placed.

The cases B project below the ship's bottom, about to the under side of the keel, and have apertures b b

at their lower sides, near the rim, and an opening, b, in the lower face of each, just in rear of the side apertures.

Inclined guards a a run from suitable points of the ship's bottom backward, so as to cover the front sides of the projecting parts of the cases B B, and let the water slip over them.

The rear ends of the guards a may terminate at such points in the rims of the cases as may seem desirable.

Within the cases B are the wheels C, one to each case, and as many wheels and cases as wanted, all being conveniently placed on one shaft.

The cases are tight, with the exception of the apertures and openings before mentioned, and fit the wheels pretty closely.

The shaft joining the wheels is connected with the engine, which latter sets the shaft in rotation when it is desired to get the ship under way.

A few revolutions of the wheel expel the air from the case into the water, and form a vacuum therein, to fill which, water immediately rushes through the apertures b, at the sides of the case, it being prevented from entering at the opening in the rim by the passing of air out thereat, and the rotation of the wheel in a direction unfavorable to such entry. The side currents first strike the concave front faces of the buckets, which latter are inclined along the face of the wheel, as shown in the drawings, so as to confront the entering streams, and receive the impact of the latter, which immediately increases the speed of the wheels.

Whenever the currents enter from both sides, as they do when the wheels are vertically placed, the latter are provided with double concave buckets c c, each pair inclined from the sides of the wheel toward, and meeting at a common point in the middle line of the rim.

Where the currents enter only at one side, as when the wheels are horizontally located, the buckets are single, and inclined across the whole face of the wheel.

The side currents are arrested by meeting each other at the middle line of the rim of the wheel, or the wall of the case, according as they enter at one or both sides, and form bars of water, lying transversely of the case, which bars are cut, by the sharp edges c' of the buckets, into sections, that are thrown out of the opening b', in the rim of the case, by the concave rear faces c' of the buckets. The dense water to the rear of the cases, reacting upon the ejected volumes, materially adds to the speed of the wheel.

It will be seen that this is not an invention of that sort in which water in its ordinary condition is allowed to flow into the wheel at the sides thereof, and be ejected by centrifugal force at the rim. The essence of my invention is the formation of a vacuum within the case, and the consequent sudden and forcible in-

jection of the side currents against the confronting inclined faces of the buckets, the water being, so to speak, prepared for use, and wrought up into a condition differing from its normal state, by its withdrawal from the main mass in the form of the transverse streams, which previous preparation increases very highly its efficiency when it comes to play upon the wheel.

The side apertures are controlled by slides, to regulate the volume of supply.

The principle herein described is also applicable, in a very advantageous manner, to force-pumps, by suitably reducing the size of the wheel and enclosing-case, providing gearing for the rotation of the former, and applying a spout or hose to the opening in the rim, out of which water is thrown.

The case should be placed in the reservoir of water at a depth sufficient to keep the side apertures always covered.

It is thought that a pump of this sort may be made to subserve a very useful purpose as a fire-extinguisher, as it will throw or elevate water to great distances, according to the speed at which the wheels may be run.

Having thus described my invention, What I claim as new, and desire to secure by Letters Patent, is—

1. The method, herein described, of propelling ships and raising water by means of the direct action of side currents, drawn by a vacuum, upon the buckets of a wheel working within an enclosing-case, and the reaction of the dense outside water upon the volumes thrown out of such case by the wheel, substantially as described.

2. The radial buckets *c*, inclined across the periphery of the wheel, and provided with concave front and rear faces, and side cutting-edge, as and for the purpose set forth.

In witness whereof, I have hereunto set my hand and seal.

COLIN T. FINLAYSON. [L. S.]
